[57] **CLAIM**

The ornamental design for a container and seal, as shown and described.

DESCRIPTION

FIG. 1 is a top perspective view of a container and seal showing the new design;

FIG. 2 is a top perspective view thereof with the seal exploded;

FIG. 3 is a side elevational view thereof with the seal exploded, all sides being the same;

FIG. 4 is a top plan view of the seal;

FIG. 5 is a bottom plan view of the seal;

FIG. 6 is a top plan view of the container;

FIG. 7 is a bottom plan view of the container;

FIG. 8 is a vertical cross-sectional view thereof; and,

FIG. 9 is a vertical cross-sectional view thereof with the seal exploded.

The seal of FIGS. 4 and 5 and the container of FIGS. 6 and 7 are shown separately for clarity of illustration.
